UNITED STATES PATENT OFFICE.

RICHARD G. DUNWODY, OF ATLANTA, GEORGIA.

ARMOR FOR TIRES.

980,930.

Specification of Letters Patent. Patented Jan. 10, 1911.

Application filed June 20, 1910. Serial No. 567,864.

To all whom it may concern:

Be it known that I, RICHARD G. DUNWODY, a citizen of the United States of America, residing at Atlanta, in the county of Fulton 5 and State of Georgia, have invented certain new and useful Improvements in Armor for Tires, of which the following is a specification.

This invention relates to a protective 10 armor for pneumatic tires, the object of the invention being to provide a structure adapted to lie inside of the outer casing of a tire and to protect the inner tube thereof against puncture.

15 Further objects and advantages of the invention will be set forth in the detailed description which now follows:

In the accompanying drawing, Figure 1 is a transverse section of the outer casing of a 20 pneumatic tire with the inner tube omitted, and with the protective armor in place, Fig. 2 is a longitudinal sectional view of a portion of the tire shown in Fig. 1, upon a reduced scale and upon line 2--2 of Fig. 1, 25 and, Fig. 3 is a sectional perspective view of the armor adapted for use with a slightly modified shape of tire.

Like numerals designate corresponding 30 parts in all of the figures of the drawing.

Referring to the drawing, the numeral 5 designates the outer casing of a tire. The protective armor comprises a bowed annulus 6 of sheet metal so shaped in cross section as to conform closely to the inner periphery of 35 the casing 5. This annulus 6 is preferably of steel, though it may be formed of other metal if desired. A casing 7, preferably of canvas incloses the annulus 6 and also in closes a raw cotton packing 8. The term 40 "annulus" is used in the sense that the member 6 extends entirely around the wheel longitudinally of the tire. The inner free ends of the armor composed of the members 6, 7, and 8, are engaged in a keeper 9. This 45 keeper is in the nature of an annulus and its sides are open for the reception of the free edges of the protective armor, as is clearly shown in the drawing. The inner tube has been omitted in the drawings, but it will be 50 understood that it lies within the armor herein shown and described.

It will be apparent from an inspection of the drawings that the armor forming the subject matter of the present invention is 55 independent of the casing 5 so that it is capable of being removed bodily therefrom.

This renders it applicable to different wheels, renders it possible to transfer it from one wheel to another, and renders it applicable to the tires already in use. 60

While I have shown the armor separate from the outer casing in Fig. 1, it is apparent that it may be secured thereto if desired. It is a well known fact, that raw cotton is very efficient in deflecting pointed objects, 65 such for instance as tacks, nails, and the like. An object such as a tack or nail must penetrate the two thicknesses of canvas forming the casing 7, the raw cotton and the steel annulus before it can reach the inner tube. 70 It is apparent that it would be quite impossible for this to occur.

The armor herein shown and described serves another useful purpose. It is a well known fact that more deflated tires are 75 caused by blow-outs than by direct punctures. In an ordinary tire, the flexing of the casing 5 occurs principally at the point indicated by the arrow "a" in Fig. 1. This is the point close to where the clincher rim 80 engages the tire and the constant flexing of the tire at this point, causes it to rim-cut and to crack longitudinally of the tire. It will be noted that that portion of the armor lying 85 behind the point indicated by the arrow "a" is straight. This reinforces the tire at the point indicated by the arrow "a" and the armor tends more readily to flex at about the point indicated by the arrow "b". This has 90 a tendency to cause the casing 5 to be flexed adjacent the point indicated by the arrow "b", and since the casing is flexed over this rounded surface of considerable radius, its bend at any one point is not very great and it consequently will not crack so readily. 95 Furthermore, rim-cutting is thereby absolutely prevented.

From the foregoing description, it will be seen that simple and efficient means are herein provided for accomplishing the objects of the invention, but while the elements shown and described are well adapted to serve the purposes for which they are intended, it is to be understood that the invention is not limited to the precise construction set forth, but includes within its purview such changes as may be made within the scope of the appended claims. 100

Having described my invention, what I claim is: 110

1. A reinforcing armor for tires comprising a bowed annulus, a packing of raw cot-

ton surrounding said annulus, a canvas casing inclosing both the annulus and the raw cotton, and a keeper member with which the free ends of said armor has sliding engagement.

2. A reinforcing armor for tires comprising a bowed annulus, a packing of raw cotton surrounding said annulus and a canvas casing inclosing both the annulus and the 10 raw cotton, said armor having its terminal portions extending in straight lines and

lying closely against the inner periphery of the tire casing, and an annular keeper of channel form adapted to receive the free edges of the armor.

In testimony whereof I affix my signature in presence of two witnesses.

RICHARD G. DUNWODY.
